UNITED STATES PATENT OFFICE

CHARLES H. GAIL, OF LOS ANGELES, CALIFORNIA, ASSIGNOR TO LOS ANGELES SPRING
BED COMPANY, OF LOS ANGELES, CALIFORNIA, A CORPORATION OF OHIO

BEDSPRING

Application filed October 13, 1924. Serial No. 743,304.

This invention has to do with a bed spring, and it is an object of the invention to provide a bed spring, which is applicable to beds of various types. 5 There are different types of beds in common use requiring springs of different shapes. One of these types is the straight end bed, the ends of which are straight; another is the bow end bed having the one end at least, 10 with its corners bowed or turned inwardly. The ends of a bed spring made to fit a straight end bed must be straight and must have substantially square corners, while one end, at least, of a bed spring to properly fit a bow end bed, must have its corners bowed, cut away or indented. Because of this situation, 15 a person is compelled to buy a different bed spring every time he buys a bed of a different type, and merchants are compelled to keep an assortment of both types of springs in order 20 to properly supply the trade. In an attempt to overcome this situation springs have been made in the usual rectangular form, only narrower at one end than standard width so 25 that they can be put in a bow end bed. This undersize spring is not satisfactory in that it does not properly fit either type of bed, and will not properly support a mattress.

It is an object of this invention to provide 30 a full size spring, which is applicable to bow end and straight end beds.

Another object of this invention is to provide 35 a spring with an adjustable end whereby it can be fitted to beds of different types.

Another object of this invention is to provide 40 a spring of the character above mentioned, which is simple and inexpensive of construction, and simple and convenient to handle and operate.

The various objects and features of this 45 invention will be best and more fully understood from the following detailed description of typical forms thereof throughout which description reference is had to the accompanying drawings in which:

Fig. 1 is a plan elevation of a corner of a bed spring constructed in accordance with this invention showing the corner in shape to 50 fit an ordinary straight end bed.

Fig. 2 is a view similar to Fig. 1 showing the corner in shape to fit a bow end bed.

Fig. 3 is an enlarged detailed sectional view of the corner taken as indicated by line 3—3 on Fig. 1. 55

Fig. 4 is an enlarged detailed sectional view of the corner taken as indicated by line 4—4 on Fig. 1.

Fig. 5 is an enlarged detailed sectional view of a part of the corner taken as indicated by line 5—5 on Fig. 1. 60

Figure 6 is a side view of that part of the device shown in Figure 5.

Figure 7 is a vertical section through Fig- 65 ure 5.

Fig. 8 is a diagrammatic view of a complete bed spring embodying this invention showing the spring in shape to fit a straight end bed. 70

Fig. 9 is a diagrammatic view of a bed 70 spring similar to Fig. 8 showing the spring in shape to fit a bow end bed.

Fig. 10 is a view similar to Fig. 1 showing another form of the invention.

Fig. 11 is a detailed view similar to Fig. 10 75 showing the corner arranged in one manner to fit a bow end bed.

Fig. 12 is a view similar to Fig. 11 showing the corner arranged in another manner to fit a bow end bed. 80

Fig. 13 is an enlarged detailed sectional view of the corner shown in Fig. 10—11—12 being a view taken as indicated in line 13—13 in Fig. 10. 85

Fig. 14 is an enlarged detailed sectional view of a part of the corner shown in Fig. 10 being a view taken as indicated by line 14—14 on Fig. 10.

Bed springs usually comprise a base frame adapted to rest on or be supported by the bed, a top frame adapted to support a mattress, and a plurality of small springs, usually helical springs, which support the top frame on the base frame. The top frame of a spring is usually substantially rectangular 90 in form and is proportioned to more or less accurately fit the bed in which it is to be used, so that it will properly support the mattress. As stated above, the ends of a bed spring to fit a straight end bed must be the 95 100

full width of the bed spring, and must be substantially square, while at least one end of a spring to fit a bow end bed must be less than the full width so that it will fit the bed without interference.

5 It is a primary object of this invention to provide a bed spring which will properly fit beds of different types, for instance, straight end or bow end beds. The present invention is in no way connected with the 10 general construction of the bed spring, that is, as to the arrangement or construction of the supporting springs or the manner of bracing the frames so therefore no reference 15 will be made to such features.

15 In the following detailed description, reference will be made to a bed spring frame suitable for the top frame of a bed spring, it being understood, however, that the construction described is also applicable to the 20 base frame if required, and to either or both ends of the frame.

The bed spring frame 10 illustrated in the drawings, includes longitudinal sides 11, a 25 transverse head end 12, and a transverse foot end 13. The frame 10 is formed of a bar round in cross sectional configuration and is simple in design and construction.

30 In accordance with this invention the foot end, and if desired, the head end also, of the frame 10 is constructed so that it is variable or adjustable as to shape, for instance width, so that it can be fitted to beds of different types. It is generally preferred to cut away 35 the corners of the frame, for instance, at the foot end thereof, and to provide corner pieces suitable for placement in and removal from the cut away parts.

35 In Figures 1 to 9 of the drawings, I illustrate a frame or corner construction which is particularly simple, effective and practical.

40 In this form of construction each foot end corner of the frame 10 is indented so that it has a part 15, extending transversely inwardly from the side 11 at a point substantially removed from the end of the frame, and part 16, extending longitudinally inwardly from the foot end 13 at a point removed from the side of the frame. The inner ends of the 45 parts 15 and 16 join so that the indentation has a substantially square inner corner. A corner piece 17 is adapted to be positioned in or at the indentation to fill out the corner so that it is substantially square, as in the 50 case of an ordinary frame made to fit a straight end bed, and is adapted to be removed from the indentations so that the corner of the frame is shaped or cut away in substantially the manner of a frame constructed to fit a bow end bed.

55 The corner piece 17 may comprise an L shaped body having a side part 18, and an end part 19, at substantially right angles to each other. The side part 18 and end part 60 19 of the body are shaped and proportioned

so that they will fit and fill the corner of the frame 10, and so that they practically form continuations of the side 11, and end 13, respectively. In the particular form of construction now under consideration, the corner 70 piece 17 is connected with frame 10 so that it can be slid from a position where it occupies the corner or indentation to a position where it is out of the corner or indentation. The side part 18 may be formed of angle iron as 75 illustrated in the drawings.

80 The corner piece 17 may include, in addition to the frame above described a plate 20 connected to the side 18 of the frame to extend inwardly therefrom, so that it extends between the side part 18 and the longitudinal part 16 of the indentation when the corner piece is in position in the corner as illustrated in Fig. 1. The corner piece in this case is mounted to slide transversely of the frame 10 to a position such as is illustrated in Figure 2. A suitable connection may be made between the corner piece and frame by providing an extension 21 on the plate 20 to extend around the transverse part 15 of the recess and by slidably connecting the end part 19 of the frame with the end of the frame 10. In the particular construction illustrated in the drawings, the connection between the part 18 and end 13 is had by providing an 90 end 25, on the end part 19, with an opening 26 to slidably carry the end part 13 of the frame 10 and by connecting a flange part 26 to the end part 19 to form a channel which 95 will slidably receive the end 13. The flange part 26^a may be attached to the end part 19 by means of rivets as clearly illustrated in the drawings. With this form of construction, the connection between the part 18 and end 13 is had by providing an 100 end 25, on the end part 19, with an opening 26 to slidably carry the end part 13 of the frame 10 and by connecting a flange part 26 to the end part 19 to form a channel which 105 will slidably receive the end 13. The flange part 26^a may be attached to the end part 19 by means of rivets as clearly illustrated in the drawings. With this form of construction, it is desirable to turn the inner edge 28 of the plate 20 downwardly to form a 110 stop to limit the outward movement of the corner piece so that it can not be moved outward beyond the position illustrated in Fig. 1. In practice the various parts may be proportioned and fitted so that the corner piece will not slide or shift accidentally but will move only when deliberately operated.

115 From the foregoing description, it will be apparent that the corner pieces 17 can be easily extended into position to occupy the indentations at the corners of the frame, as illustrated in Figs. 1 and 8, or can be retracted or slid in so that they leave the indentation in the spring frame substantially clear or open, as illustrated in Figs. 2 and 9. When the corner pieces are in the position illustrated in Figs. 1 and 8, the spring will properly fit a straight end bed and when they are in the position illustrated in Figs. 2 and 9 the spring will properly fit a bow end bed.

120 In Figures 10 to 14 inclusive, is illustrated a somewhat different form of construction embodying the invention. In this form of construction the corner of the spring frame 125

may be indented in the manner above described. Each corner piece 17^a, in this case is in the form of a plate 40 shaped to more or less accurately fit or fill the indentation in the frame 10. The plate 40 is provided at its inner edge with downwardly and then outwardly turned ears 41, which form clips to receive and hold the longitudinal part 16 of the recess, and at its inner edge with a similar ear 42 adapted to receive and hold the transverse part 15 of the recess. With this construction the corner piece can be completely detached from the frame by manipulating it so that the ears are sprung to release the parts 15 and 16, or it may be swung to a position removed from the indentation by sliding it in the direction indicated by the arrow "A" in Fig. 10 to release the ear 41 from the transverse part 15, of the recess and then swinging it back or inwardly, or, sliding it somewhat outwardly, in a direction opposite to that indicated by the arrow "A" in Fig. 10, and then allowing it to swing down so that it hangs down from the part 16, of the indentation. In addition to or in substitution for the connection just described one or more ears 45 may be provided at the outer edge of the plate 40 in addition to ears 41 at the inner edge of the plate 40 so that the plate can be slid longitudinally out of the indentation in the frame so that the ear 45 passes over or receives the side 11 of the frame 10 while the ears 41 pass off of or release the longitudinal part 16 of the indentation. With this last mentioned form of connection it is desirable to provide a clip or ear 50 at the outer end of the plate 40 to receive and hold the transverse part 15 of the indentation when the plate is removed from the indentation.

Having described only typical forms of my invention I do not wish to limit myself to the specific details hereinabove set forth but wish to reserve to myself any changes or variations that may appear to those skilled in the art or fall within the scope of the following claims.

I claim:

1. In combination, a bed spring frame having a head portion and side portions, the head portion being joined to each side portion by a portion extending from the head portion inwardly of the frame and parallel to the side portion and then outwardly to the side portion and parallel to the end portion whereby to form re-entrant right angled corners, sliding corner pieces each forming a continuation of the head portion and a respective side portion of the frame, each corner piece having one end slidably engaged on the head portion, and means to connect the remaining end slidably to the portion of the re-entrant corner parallel to the head.

2. In combination, a bed spring frame having a head portion and side portions, the

head portion being joined to each side portion by a portion extending from the head portion inwardly of the frame and parallel to the side portion and then outwardly to the side portion and parallel to the end portion whereby to form re-entrant right angled corners, sliding corner pieces each forming a continuation of the head portion and a respective side portion of the frame, each corner piece having one end slidably engaged on the head portion, and means to connect the remaining end slidably to the portion of the re-entrant corner parallel to the head and consisting of a plate having a projection embracing the last mentioned re-entrant corner portion, said plate resting on the remaining part of the re-entrant corner.

3. In combination, a bed spring frame having an end portion and a side portion joined by a portion extending from the end portion inwardly of the frame and then outwardly to the side portion forming a re-entrant corner, a frame corner piece formed separate from the said portions of the frame, and means for holding the corner piece in connection with said portions of the frame in the re-entrant corner, said means including a channel-shaped part on the corner piece embracing one of said portions of the frame.

4. In combination, a bed spring frame having an indented portion in the corner thereof, a corner-piece associated with said frame and arranged to fill out said indented portion, and means on the corner-piece movably engaging the same with the frame whereby the corner-piece may be moved into and out of position relative to the indented portion.

5. In combination, a bed spring frame having an indented portion in the corner thereof a corner-piece associated with said frame and arranged to fill out said indented portion, and means at one end of the corner-piece movably engaging the corner-piece with the frame, whereby the corner-piece may be moved into and out of closing position relative to the indented portion.

6. In combination, a bed spring having an indented portion at the corner thereof, and a corner-piece having means slidably engaging the end part of the frame and arranged when in its outer-most position relative to the frame to close the space formed by said indented portion, said means permitting inward movement of the corner-piece while engaging the frame.

7. An article of manufacture comprising a corner-piece adapted to fill out the indented corner of a bed spring frame, said corner-piece having means slidably engaging the frame to fill out the indented corner.

8. An article of manufacture comprising a corner-piece adapted to fill out the indented corner of a bed spring frame, said corner-piece having a channel portion formed

in one end thereof for slidably engaging the adjacent portions of the frame.

9. In combination, a bed spring frame having an end portion and a side portion joined by a portion extending from the end portion inwardly of the frame and then outwardly to the side portion forming a re-entrant corner, a corner-piece formed separate from the said portions of the frame, and means for slidably connecting the corner piece with 10 said portions including a part on the corner-piece slidably engaging the end portion of the frame, and a part on the corner-piece slidably engaging the portion of the spring frame extending outwardly to the side portion of 15 the frame.

10. In combination, a bed spring frame having an end portion and a side portion joined by a portion extending from the end portion inwardly of the frame and then outwardly to the side portion forming a re-entrant corner, a corner-piece formed separate from the said portions of the frame, and means for slidably connecting the corner-piece with said portions including a part on the corner-piece slidably engaging the end portion of the frame and a part on the corner-piece slidably engaging the portion of the spring frame extending outwardly to the 25 side portion of the frame, one of the said parts on the corner-piece being channel shaped.

11. For optional use upon a spring-steadying frame having a "dented" corner adapting it to interfit within a bow end; an adapter 35 which is provided with means for its attachment to said frame and is shaped to rectify the "dented" corner thereof, said attachment means comprising a plurality of fingers adapted partially to surround said frame.

12. For optional use upon a spring-steadying frame having a "dented" corner adapting it to interfit within a bow end; an adapter 45 which is provided with means for its attachment to said frame and is shaped to rectify the "dented" corner thereof, said attachment means comprising a plurality of fingers adapted partially to surround said frame, like 50 fingers being disposed near the respective ends of said plate.

13. For optional use upon a spring-steadying frame having a "dented" corner adapting it to interfit within a bow end; an adapter 55 which is provided with means for its attachment to said frame and is shaped to rectify the "dented" corner thereof, said attachment means comprising a plurality of fingers adapted partially to surround said frame, like 60 fingers being disposed near the respective ends of said plate, and additional fingers being disposed therebetween.

14. The combination with a bed-bottom frame for bow-foot beds, said frame comprising sides and ends forming a generally

rectangular open framework having at an angle a reentrant portion at which the frame extends inwardly from a side and then outwardly to an end, of a movable plate for filling out the reentrant portion, said plate having means movably engaging a portion of the frame beyond the reentrant portion and other means adapted to engage with a part of the reentrant portion when the plate is in filling position. 75

15. The combination with a bed-bottom frame for bow-foot beds, said frame comprising sides and ends forming a generally rectangular open framework having at an angle a reentrant portion at which the frame extends inwardly from a side and then outwardly to an end, of a movable plate for filling out the reentrant portion, said plate having means comprising lugs forming continuations of two edges of the plate, said lugs 80 partially surrounding portions of the frame adjacent thereto.

16. Means for filling out to complete rectangular form a corner of a bed-bottom frame having reentrant corners adapting it for use 85 with bow-foot beds, said means including a plate having means on two adjacent edges forming continuations thereof adapted to partially surround portions of the frame near a corner. 90

In witness that I claim the foregoing I have hereunto subscribed my name this 26 day of April 1924.

CHARLES H. GAIL.
